UNITED STATES PATENT OFFICE.

EDWARD A. FARR, OF MERIDEN, CONNECTICUT, ASSIGNOR TO MANNING BOWMAN & COMPANY, OF MERIDEN, CONNECTICUT, A CORPORATION OF CONNECTICUT.

DESIGN FOR A TRAY-HANDLE.

45,745.

Specification for Design.

Patented May 12, 1914.

Application filed February 6, 1914. Serial No. 817,078. Term of patent 7 years.

To all whom it may concern:

Be it known that I, EDWARD A. FARR, a citizen of the United States, residing at Meriden, New Haven county, Connecticut, have invented a new, original, and ornamental Design for Tray-Handles, of which the following is a specification, reference being had to the accompanying drawing, forming a part thereof, in which—

Figure 1 is a top plan view of my new design of handle as applied to a tray a portion

of a tray structure being shown in dotted lines. Fig. 2 is a perspective view of the handle detached.

I claim:

The ornamental design for a tray handle, as shown.

EDWARD A. FARR.
